SOUND RADIATOR TRUMPET

Alex Robbins, 147—33 84th Drive, Jamaica 35, N.Y.

Filed Apr. 27, 1962, Ser. No. 69,874

Term of patent 14 years

(Cl. D26—14)

FIG. 1 is a perspective view of a sound radiator trumpet according to my invention; and FIG. 2 is a front view of FIG. 1.

The dominant features of the design reside in the portion shown in full lines.

I claim:

The ornamental design for a sound radiator trumpet, as shown and described.
